ATTORNEYS

UNITED STATES PATENT OFFICE.

WALTER A. GARRATT, OF COVINGTON, KENTUCKY.

PNEUMATIC HORN.

Application filed May 20, 1920. Serial No. 382,910.

To all whom it may concern:

Be it known that I, WALTER A. GARRATT, a citizen of the United States, and a resident of Covington, Kenton County, Kentucky, have invented certain new and useful Improvements in Pneumatic Horns, of which the following is a full, clear, and exact description, reference being had to the drawings, forming a part of this specification.

10 My invention relates to horns, or signals, operated by air suction, and has application chiefly to motor vehicle warning signals, although its range of use need not be confined to this, as will be apparent.

15 The essential principle of my invention embodies the employment of what may be characterized as a vacuum motor coupled to the intake manifold or suction side of the motor vehicle engine to actuate a hammer or striker for setting up sound producing vibrations in the diaphragm of any suitable horn. With this object in view, I have designed the construction as will be herein-after particularly pointed out and claimed,

20 so that I am enabled to produce a sound of startling character with a minimum expenditure of suction and thus to operate the horn with practically no loss of engine power.

25 In the drawings, Figure 1 is a sectional view of the device. Figure 2 is a perspective view of the two intermediate vibratory devices, one of which provides spring means for retaining the valve.

30 Fig. 3 is a plan view of one of the disks of the bellows.

The sound projecting element or horn is shown at 1, which is flanged out at 2 and 40 mounted on a conical casing 3. The casing has mounted thereon a bracket 4 over which is mounted the shell 5. The pipe 6 running from the intake manifold of the engine, communicates with a bellows device which in 45 its turn imparts vibration to a diaphragm 7 mounted against the flanged portion 2 of the horn or projector and carrying a sound amplifying device. Instead of a metal diaphragm some other mechanical sounding device could be substituted.

50 The diaphragm has secured thereon centrally the washers 8 which carry an adjustable post 9. This post 9 acts as an anvil to receive the blows of the hammer or striker 55 by means of which the diaphragm is set into vibration.

The bellows device comprises a number of disks 10 which are soldered together at their peripheries, and are made of thin resilient metal so that the assembly will act 60 as a bellows. The disks are perforated with a central hole, 10^a.

The number of disks and, therefore, the bellows sections may be varied as may be desired, the object being to provide sufficient surface area to accomplish the results which may be attained within considerable limits by decreasing the number and increasing the surface diameter of the bellows or vice versa.

65 The exact connection to the suction pipe with the bellows comprises a union 11, connected to a fitting 12 mounted in the bracket. On this fitting is firmly soldered the rear-most disk of the bellows assembly.

70 At the central opening in the foremost one of the disks is mounted the flanged ring 13, which is also firmly soldered into place. Loosely mounted in the bellows opening is a stop post 15 with its head 15^a guided in 80 the fitting 12. This post is provided with a nut 14 which abuts against the end of the fitting so that the distance between the end of the post and the bellows valve may be adjusted as desired.

75 The flanged ring 13 carries or is firmly united to the cruciform plate 16, which carries preferably a pair of bent spring arms 17, terminating adjacent each other in notched ends, which serve to mount the stem 90 button 18 of a valve 19, although a single spring arm would also serve the purpose. This valve 19 is held by the spring arms in contact with the flanged ring 13, and the valve is displaced by means of the bellows 95 device pulling rearwardly on the cruciform plate until the post 15 contacts with the valve.

85 The vacuum on the inside of the bellows caused by the engine suction with the atmospheric pressure without, initiates the movement of the bellows with the valve 19 closed until the movement of the valve inwardly is stopped, opening the valve and equalizing the pressure, causing the bellows plates to 100 return to normal position and thus again closing the valve. It will be evident that the area of the bellows plates and the number of the plates will determine the power of the device. If the valve instead of floating with 110 its seat were held against movement, a more rapid movement of the bellows would be ob-

tained but the stroke, so to speak, would be much less powerful.

The cruciform plate 16 also carries an arched plate 20, which has a small double elliptic plate spring device 21 on its central portion. It is this device 21 which carries a weight member 22 which serves as the hammer in striking the anvil post at the center of the diaphragm.

- 10 The spring 21 upon which the hammer 22 is mounted thus gives a resilient stroke to the hammer, and by adjusting the anvil post 9 in the diaphragm a succession of extremely rapid and comparatively powerful blows are delivered on the diaphragm to cause an extremely loud and discordant set of sound vibrations. The vibration of the bellows itself and of the elliptical spring member 21 also adds to the starting noise produced by the
- 15 20 device the moment the bellows is opened to the engine suction by the opening of the valve in the pipe 6 which is not shown.

While I have illustrated my invention in the form as to details which I have found 25 preferable, it will be understood that these specific details may be varied within wide limits without departing from the spirit of my invention which, as I have already indicated, relates to the employment of a 30 vacuum bellows motor actuated by engine suction to cause a rapid hammer stroke on the diaphragm of the horn.

Having thus described my invention, what I claim as new and desire to secure by Letters Patent, is:—

1. In a sounding device the combination of a pneumatic vibratory member and a mechanical sounding device and means carried by said member for setting up vibrations in 40 the mechanical sounding device, said pneumatic vibratory member comprising interconnected resilient plates, with openings through the plates to form an inner compartment and a valve to close the compartment.
- 45 2. A pneumatic vibratory member comprising a series of plates of resilient nature, said plates having apertures between their peripheries and jointed in an air tight manner at the peripheries, means for subjecting 50 said member to pneumatic action, and a mechanical sounding device, with means intermediate the pneumatic member and the sounding device for setting up vibrations in the latter device.
- 55 3. A pneumatic vibratory member comprising a pipe element, a series of plates united at the peripheries and having apertures therethrough, means for connecting the pipe element to the said apertured portion of the assembly and a valve mounted over the opposed apertured portion of the assembly, and means for unseating 60 the valve upon pneumatic action exerted through the pipe element upon the assembly, and a mechanical sounding device, with

means intermediate the pneumatic member and the sounding device for setting up vibrations in the latter device.

4. In a device of the character described, the combination with a pneumatic member 70 comprising a plurality of interconnected plates, means for applying air power thereto, a valve mounted thereon for interrupting the air power upon movement of the member, a spring member carried also on the 75 pneumatic member, and a mechanical sounding device lying in the path of the spring member whereby vibration of the pneumatic member will cause a vibratory hammer on the sounding member. 80

5. In a device of the character described, the combination of a pneumatic member comprising a plurality of interconnected plates, means for supplying air power thereto, a valve mounted thereon for interrupting the air power upon the pneumatic member to vibrate the pneumatic member, spring means for maintaining the valve upon its seat, and a fixed member to act as an unseating stop for the valve upon motion of the pneumatic 90 member. 85

6. In a device of the character described, the combination of a pneumatic member comprising a plurality of interconnected plates, means for supplying air power thereto, a valve mounted thereon for interrupting the air power upon the pneumatic member to vibrate the pneumatic member, spring means for maintaining the valve upon its seat, said spring means being likewise 100 mounted on the pneumatic member, and a fixed member to act as an unseating stop for the valve upon motion of the pneumatic member. 95

7. In a device of the character described, the combination of a pneumatic member comprising a plurality of interconnected plates, means for supplying air power thereto, a valve mounted thereon for interrupting the air power upon the pneumatic member to vibrate the pneumatic member, spring means for maintaining the valve upon its seat, said spring means being likewise mounted on the pneumatic member, and a fixed member to act as an unseating stop 110 for the valve upon motion of the pneumatic member, and a spring structure mounted on the pneumatic member adapted for variation 115 of the vibratory movements thereof.

8. In a device of the character described, the combination of a pneumatic member comprising a plurality of interconnected plates, means for supplying air power thereto, a valve mounted thereon for interrupting the air power upon the pneumatic member to vibrate the pneumatic member, spring means for maintaining the valve upon its seat, said spring means being likewise 120 mounted on the pneumatic member, and a fixed member to act as an unseating stop for 125 the valve upon motion of the pneumatic member, and a spring structure mounted on the pneumatic member adapted for variation of the vibratory movements thereof. 130

the valve upon motion of the pneumatic member, a spring structure mounted on the pneumatic member adapted for variation of the vibratory movements thereof, and sound-
5 ing means lying in the path of the spring member for contactual hammering, to set up sound vibrations of the sounding means.

9. In a device of the character described, the combination of a pneumatic member
10 comprising a plurality of interconnected plates, means for supplying air power thereto, a valve mounted thereon for interrupting the air power upon the pneumatic member to vibrate the pneumatic member, spring
15 means for maintaining the valve upon its seat, said spring means being likewise mounted on the pneumatic member, and a fixed member to act as an unseating stop for the valve upon motion of the pneumatic
20 member, a spring structure mounted on the pneumatic member adapted for variation of the vibratory movements thereof, and a dia-
phragm lying in the path of the spring member for contactual hammering thereby.
25 10. In a device of the character described, the combination of a pneumatic member comprising a plurality of interconnected plates, means for supplying air power thereto, a valve mounted thereon for interrupt-
30 ing the air power upon the pneumatic member to vibrate the pneumatic member, spring means for maintaining the valve upon its seat, said spring means being likewise mounted on the pneumatic member, and a
35 fixed member to act as an unseating stop for

the valve upon motion of the pneumatic member, a spring structure mounted on the pneumatic member adapted for variation of the vibratory movements thereof, and a dia-
40 phragm lying in the path of the spring member for contactual hammering thereby, said diaphragm having an adjustable anvil member thereon to receive the hammering contact.

11. In a device of the character described, the combination of a pneumatic member comprising a plurality of interconnected plates, means for supplying the air power thereto, a valve mounted thereon for interrupting the air power upon the pneumatic member to vibrate the pneumatic member, spring means for maintaining the valve upon its seat, said spring means being likewise mounted on the pneumatic member, and a fixed member to act as an unseating
50 stop for the valve upon motion of the pneumatic member, said fixed member being adjustable to control the point of unseating of the valve.

12. In a sounding device, a bellows struc-
ture, means for setting up a suction therein, a valve carried by the bellows, fixed means for unseating the valve, spring means for mounting the valve on the bellows, a double elliptic spring carried by the bellows, a dia-
55 phragm, and a hammer mounted on the spring on the outside thereof to contact with the diaphragm upon the vibrations of the bellows.

WALTER A. GARRATT.
